United States Patent Office

Des. 206,511
Patented Dec. 20, 1966

206,511

FROZEN CONFECTION OR SIMILAR ARTICLE

Roscoe T. Fowler, 254 N. St. John Lane,
Ellicott City, Md. 21043

Filed Oct. 15, 1965, Ser. No. 87,500

Term of patent 14 years

(Cl. D82—2)

FIGURE 1 is a side elevation view of a frozen confection or similar article, showing my new design;

The essential features of the design reside in the portions shown in solid lines.

I claim:

The ornamental design for a frozen confection or similar article, as shown and described.
